By Henry O. M. M. S. atty.

UNITED STATES PATENT OFFICE.

STANLEY L. MACDONALD, OF CAULFIELD, VICTORIA, AUSTRALIA.

TOY ROCKER.

Application filed February 23, 1921. Serial No. 447,288.

To all whom it may concern:

Be it known that I, STANLEY LAYTON MACDONALD, a subject of the King of Great Britain, of Caulfield, in the State of Victoria, Commonwealth of Australia, have invented certain new and useful Improvements in Toy Rockers, of which the following is a specification.

The present invention refers particularly to wooden horses or like toys shaped to resemble the configuration of quadrupedal animals capable of bearing the entire weight of a child or adult and provided with a curved base or rockers so as to be capable of rocking and has been devised to provide a construction of the same whereby progression by steps may be effected.

In the accompanying drawings illustrating the invention:—

20 Fig. 1 is an elevation of the improved toy animal rocker with parts in section, and

Figs. 2 and 3 are similar views to Fig. 1 illustrating the motions that cause step progression.

25 As illustrated the pair of curved rockers disposed one at each side of the animal are separable at 1 to form two pairs of rockers 2—3 in longitudinal alinement the former being fixed to the front legs 4 rigidly ex-

30 tending from the body 5 and the rockers 3 affixed to the pair of hind legs 6, the upper portions of which enter slots 7 formed in the hollow body and are mounted on a pivot 8 at a point approximately about the centre of

35 weight. The legs are strengthened by means of metallic straps 19 which are secured to the rockers. The upper parts of the hind legs within the body are provided with pads 9 against which the interior surface of the

40 back 10 of the body abuts when the animal is backwardly tilted as in Fig. 2 thus limiting the body movement and effecting the maximum length of stride that can be taken during each rocking movement.

45 Preferably also one or both of the adjacent ends of the rockers are provided with pads 11.

By reference to Fig. 2 it will be seen that when the rider rocks the animal backwards 50 the weight is taken by the back rockers 3 and the front rockers 2 advance a prearranged distance from same and subsequently by the forward rock of the animal the weight is taken by the front rockers thus permitting 55 the hind legs to swing forward on their common pivot 8 till the front ends of the back

rockers 3 abut against the rear ends of the front rockers.

A certain amount of skill is required to obtain the fullest possible progression but 60 in order to ensure the latter a locking bar 12 is mounted on a pivot 13 in a cross bar 14 on the rear rockers and projects forward between the front legs and through a slot formed in a cross bar 15 on the front rockers. The forward end of the locking bar is either provided with a wheel or roller 16, and the underside of the bar near its forward end is formed with a notch or catch 17.

When therefore the animal is rocked back- 70 wards as in Fig. 2 the catch engages with the edge of the guide slot in the cross bar 15 when the front and back rockers are separated to the fullest extent and said cross- 75 bar 15, the pivot 13 and the locking bar 12, 80 are so arranged that the forward end of the latter or its wheel 16 will project below the front rockers 2, when the toy is in the rock- 85 ing position shewn in Fig. 2. When therefore the animal is forwardly rocked the for- 90 ward end of the locking bar or its wheel 16 contacts with the ground thus releasing the catch and permitting the hind legs and the back rockers 3, with the locking bar to move forward, and close the gap between both sets 95 of rockers.

It will be understood by the foregoing de- 90 scription that the extent of progression at each complete rocking movement is deter- 95 mined by the distance the front rockers can separate from the back rockers, the position of the pivot 8 and the distance between the back of the body and the top of the hind legs being determining factors. In the normal position Fig. 1 the rear ends of the front rock- 95 ers and the catch cross bar 15 are to the rear of the vertical plane X of the pivot 8. When the animal is in the position shewn in Fig. 2 the catch bar 15 is in advance of the vertical plane of the pivot and when the ani- 100 mal is tilted forward to such an extent that the catch cross bar is at the rear of the vertical plane X, the locking bar is released and the continued forward rocking movement permits the back rockers to swing forward 105 and end abut against the front rockers.

It will be evident, that, if for amusement purpose it is desired to progressively move the toy animal backwardly instead of forwardly the front legs will be pivoted to the 110 body instead of the back legs.

Furthermore in order to use the article as

an ordinary non-progressive toy rocker a pin 18 may be passed through the front legs and the locking bar as in Fig. 1.

I claim:

- 5 1. A toy rocking device in which the rockers are separable into two sets arranged in longitudinal alinement, one being rigidly fixed to a projection from one end of the body of the toy and the other to a projection pivoted to said body, and means to temporarily hold the rockers separated a distance apart during a portion of the rocking movement.
- 10 2. A toy animal rocking device with rockers separable into two sets arranged in longitudinal alinement, one being fixed to the rigid front legs of the toy animal and the other fixed to the hind legs, said hind legs being pivoted within the body, means to limit the relative rocking movement between said body and hind legs and means to temporarily hold the rockers separated a distance apart during a portion of the rocking movement.
- 15 3. A toy animal rocking device with rockers separable into two sets arranged in longitudinal alinement, one being fixed to the rigid front legs on the body and the other to the hind legs, said hind legs extending up through slots in the body into a cavity therein and mounted at their upper ends on a pivot extending through the body, and abutment pads on the upper portion of said hind legs within the body.
- 20
- 25
- 30

4. A toy animal rocking device with rockers separable into two sets one being fixed to the rigid front legs on the body and the other to the hind legs, said hind legs extending up through slots in the body into a cavity therein and mounted at their upper ends on a pivot extending through the body, abutment pads on the upper portion of said hind legs within the body, and a pivoted locking bar on the rear rockers provided with a catch adapted to temporarily engage a cross bar on the front rockers when the toy is backwardly rocked.

5. A toy animal rocking device with rockers separable into two sets one being fixed to the rigid front legs on the body and the other to the hind legs, said hind legs extending up through slots in the body into a cavity therein and mounted at their upper ends on a pivot extending through the body, abutment pads on the upper portion of said hind legs within the body, a longitudinal locking bar pivoted on a bar extending across the rear rockers and extending forwardly through a slot in a cross bar on the front rockers said bar having a wheel at its front end and a notched catch adapted to engage with the edge of said slot when the toy is backwardly rocked and be released by contact of the wheel with the ground.

Dated this eighteenth day of January 65
1921.

S. L. MACDONALD.
